REFRIGERATING APPARATUS

Charles R. Wayman, Dayton, Ohio, assignor, by
mesne assignments, to General Motors Corpora-
tion, a corporation of Delaware

Application November 23, 1931, Serial No. 576,632

9 Claims. (Cl. 62—4)

This invention relates to refrigerating apparatus and more particularly to control mechanisms therefor.

The objects of my invention include the providing for a refrigerating system of an improved automatically operated switch mechanism having an improved selective manual control means to be operated by the housewife for varying the operation of the refrigerating system; the provision of an improved and attractive cold control means for a domestic refrigerator; the provision of a simplified single wire or cable control for the manual control means; and the provision of a barrel type dial, improved modifying means on the switch mechanism, and improved connecting means for connecting the dial and the modifying means for indicating the effective position of the switch modifying means.

Further objects and advantages of the present invention will be apparent from the following description, reference being had to the accompanying drawings, wherein a preferred form of the present invention is clearly shown.

In the drawings:

Fig. 1 is a front view of a refrigerator embodying the invention with the machinery compartment exposed;

Fig. 2 is a fragmentary vertical sectional view of a refrigerator cabinet showing the cold control dial;

Fig. 3 is a fragmentary horizontal sectional view on the lines 3—3 of Fig. 2;

Fig. 4 is an enlarged front view of the cold control dial shown in Fig. 1;

Fig. 5 is an elevational view of the switch mechanism, the cover of which is shown in Fig. 1;

Fig. 6 is a fragmentary view of the switch mechanism showing the control or modifying means in quick freezing position;

Fig. 7 is a fragmentary view of the switch mechanism showing the control or modifying means in defrosting position, and

Fig. 8 is a section along the line 8—8 of Fig. 5.

Referring to the drawings, and more particularly to Fig. 1, there is shown for the purpose of illustrating my invention a refrigerator cabinet 20 having a food storage compartment 21 located in the upper portion of the cabinet and a machinery compartment 22 located in the lower portion of the refrigerator cabinet. Within the machinery compartment 22 there is provided a compressor 23 for compressing the refrigerant and for forwarding the refrigerant to a condenser 24 where the refrigerant is condensed and liquefied and collected in the receiver 25. From the re-

ceiver 25 the liquid refrigerant is forwarded through the conduit 26 to an evaporator 27 where the liquid refrigerant evaporates under reduced pressure to cool the food storage compartment 21. The evaporated refrigerant is returned from the evaporator to the compressor through the return conduit 28.

An electric motor 29 is provided for driving the compressor through the pulley and belt means 30. This electric motor 29 is controlled to cause the operation of the compressor according to the pressure, and consequently the temperature, of the evaporator 27 by means of a switch means 31 (shown in Fig. 1 as enclosed within a cover) operated by means of the pressure in the return conduit 28 to which it is connected by means of a conduit 32.

A manual control means is provided for the enclosed switch 31 comprising a barrel type dial 32 having a portion projecting through an aperture in the front portion of the cabinet and connected to the switch means by a suitable cable means. It is highly desirable that this cable means be as simple, compact and durable as possible. For this reason, a single wire encased in an armored conduit is used. This manual control means is more particularly shown in Figs. 2 and 3. For the purpose of receiving this dial there is provided a notch or cavity 34 in the lower portion of the door jamb 35. Within this notch there is provided a U-shaped bracket 36 which receives a pivot pin 37 upon which the dial 32 is mounted. The dial 32 is made of some suitable material such as hard rubber or bakelite and is provided with an integral drum 38 at the side of the dial portion. The dial 32 is provided with a knurled rim having suitable indices 39 thereon for indicating the various selective positions of the manual control means. A latch means 40 comprising a latch pin 41, a latch spring 42, and a spring housing 43 is provided in the rear portion of the U-shaped bracket 36 and these members are so assembled that the latch spring 42 resiliently urges the pin 41 into engagement with the notches upon the rear portion of the dial 32 to hold the dial in any desired selective position. The drum 38 upon the dial 32 is connected by suitable cable means such as a single wire 44 to a portion of the manual control means which is mounted upon the switch structure proper. The wire 44 is fastened to the drum by a screw 95.

Referring now to Figs. 5 to 8 inclusive, there is shown a switch platform 45 having a bellows cage 46 mounted thereon at one end and pro-

vided with a pair of upstanding ears 47 which pivotally support an operating lever 48 at one end by means of a suitable pin 49. The operating lever 48 is caused to move in successive vibrations by means of the bellows 50 which is connected by means of a suitable conduit to the return conduit 28 of the refrigerating system. At the other end of the operating lever 48 there is provided a snap operating switch mechanism including a cam lever 51 pivoted at an intermediate point to the operating lever 48 by means of the pin 92 and having a cam 52 at one end which is acted upon by a cam roller 53 mounted upon a lever 54. The lever 54 is pivoted at its lower end and provided with a suitable spring 55 which presses the cam roller 53 against the cam 52. The other end of the cam lever 51 is connected by means of an insulating link 56 to a pivoted upper contact 57 of a set of switch contacts. 20 This upper contact is pivoted at 58.

At the central portion of the operating lever 48 there is connected a spring adjusting means comprising a threaded pin 60 and a pair of springs 61 and 62, one above and one below the platform 45. These springs may be adjusted by suitable nuts and lock nuts 63 and 64 positioned at the upper end of the spring 61 and at the lower end of the spring 62. As the pressure within the evaporator increases, the bellows will expand to raise the operating lever 48 against the pressure of the spring 62, thereby raising the cam lever 51 and this will cause the cam roller 53 to ride from the upper face of the cam 52 to the lower face of the cam to trip the cam lever 51 in a counter-clockwise direction and thus to close the set of switch contacts 57 and 59. As the pressure in the evaporator has decreased because of the operation of the compressor 23, the bellows 50 will contract against the pressure of the spring 61 lowering the operating lever 48 and the cam lever 51, thus causing the cam roller 53 to ride from the lower face of the cam 52 to the upper face thereof. In this way the cam lever 51 will be caused to trip in a clockwise direction and separate the switch contacts 57 and 59 to stop the refrigerating apparatus.

In addition to the opposed spring adjustment connected to the central portion of the operating lever 48, there is provided an additional adjustment means designated in general by the reference character 70 which operates upon the operating lever 48 only at the upper portion of its vibrating movement. This adjusting means 70 comprises a plunger 71 having at its lower end a head 72 which engages a free end of the operating lever 48. The downward movement of the plunger 71 is limited and therefore does not affect the opening pressure of the switch mechanism but only the closing pressure. The plunger 71 is resiliently urged in a downward direction by means of a spring (not shown) enclosed within an adjusting nut 73. This spring is adjusted by the adjusting nut 73. The adjusting means 70 is supported by means of a U-shaped bracket 74 which is mounted upon the platform 45.

A portion of the manual control means, specially constructed for use with a single wire control, is mounted upon this bracket 74. This portion 70 comprises a pivoted member 75 which is pivoted upon a screw 76 which is threaded into an upstanding ear 77 which extends upwardly from the upper portion of the bracket 74. Inasmuch as a single flexible wire connecting means is used, 75 yielding means are provided for returning the

pivoted member to retracted position and for keeping the single wire taut. A spring 78, provided for urging the pivoted member to retracted position, has its central portion coiled about the screw 76 and has a pair of legs extending from this central portion, one leg 79 which rests against an abutment 80 and the other leg 81 which rests against an abutment pin 82. In order to provide quick freezing or prolonged cycles of the refrigerating apparatus, an increased 10 resistance is provided opposing the downward movement of the operating lever 48 and thus the opening of the set of switch contacts 57 and 59 is opposed by an increased resistance. The resistance means takes the form of a pivoted lever 15 84 which is mounted upon a thick, headed, pin 85 riveted to the pivoted member 75. This pivoted lever 84 is resiliently urged in a clockwise direction by means of a suitable spring 86 which is coiled about the pin 85 and has ends extending therefrom, one engaging a pin 87 upon the pivoted lever 84 and the other engaging a tongue 88 which extends from the pivoted member 75. A suitable stop 89 is provided for the pivoted lever 84 by turning outwardly a portion of the 25 pivoted member 75. The wire 44 has been described as having an end connected to the drum 38 upon the dial 32. This wire 44 is threaded through an armored conduit 90 which is fastened to the top of the platform 45 and then threaded 30 through an aperture in the tongue 88. The wire 44 has a stop 91 at the opposite side of the tongue 88 for providing a limited movement in a clockwise direction of the pivoted member 75. 35

By rotating the dial 32 in a clockwise direction 35 as viewed in Fig. 2, one end of the wire 44 will be wrapped upon the drum 38 to slowly pull the other end through conduit 90 to pull the pivoted member 75 from retracted position to one of the selective operating positions. For example, when 40 the dial is moved from the position indicated as 1 to that indicated as 2, the outer end of the pivoted lever 84, which forms a resilient abutment, will engage the pin 92 which extends from the operating lever 48. This will provide an increased 45 resistance opposing the downward movement of the operating lever 48, and will oppose the opening of the switch contacts. In this way the operation of the compressor will be prolonged. By rotating the dial further, for example, to the 50 position indicated upon the dial as 3 or 4 (not shown), the pivoted member 75 is further rotated in a clockwise direction, moving the pivot 85 of the lever 84 closer to the pin 92, thereby providing an increased resistance by reason of 55 the shortened effective moment arm. Upon further rotation of the dial 32 to the defrosting position, not shown, the pivoted member 75 is pulled clockwise such a distance that its front end, which has a turned-in nose 93, strikes the cam lever 51 60 and separates the set of switch contacts 57 and 59 as shown in Fig. 7. This separating of the switch contacts prevents the operation of the refrigerating system until the dial is reset. By stopping the refrigerating system for a sufficient 65 length of time the cooling unit 27 will become warmer and the frost will melt therefrom.

My improved cold control is in the major part concealed. Only a portion of the manually operable dial is visible. It is simple, neat, and attractive. By providing a single wire control, the control is simplified.

While the forms of embodiment of the invention as herein disclosed constitute a preferred form, it is to be understood that other forms 75

might be adopted, all coming within the scope of the claims which follow.

What is claimed is as follows:

1. An automatic device for controlling a refrigerating system including an electric switch structure for initiating and terminating operation of the system, pressure responsive means for operating said switch structure a loading device for said pressure responsive means, and means for varying the loading of said pressure responsive means, said last mentioned means including a barrel type manually operable dial having a plurality of selective operating positions, said dial being connected to means for varying the loading of the pressure responsive means.
2. An automatic device for controlling a refrigerating system including an electric switch structure for initiating and terminating operation of the system, pressure responsive means for operating said switch structure, and means for varying the operation of said switch structure, said last mentioned means including a barrel type manually operable dial having a plurality of selective operating positions, said dial being positioned remote from said switch structure, latch means for latching said dial in any one of said selective positions, means mounted upon said switch structure for controlling the operation thereof, and means operatively connecting said last mentioned means and said dial.
3. An automatic device for controlling a refrigerating system including an electric switch structure for initiating and terminating operation of the system, means for operating said switch structure responsive to certain conditions of said refrigerating system, and means for varying the operation of said switch structure, said last mentioned means including a pivoted member mounted upon said switch structure, a resilient abutment mounted upon said pivoted member, said pivoted member having means thereon for controlling said switch structure in one position to prevent operation of the system, means for urging said pivoted member into retracted position, manually operable means mounted remotely from said switch structure for controlling the position of said pivoted member, said manually operable member having a plurality of selective positions, latch means for retaining said manually operable member in any one of said selective positions, means for operatively connecting said manually operable member and said pivoted member, said manually operable means when in one position being adapted to move said pivoted member from retracted position to cause said resilient abutment to engage said switch structure, and when in another position to cause said means on said pivoted member to prevent operation of the system.
4. An automatic switch for controlling a refrigerating system including an electric circuit, a switch structure including an operating member having means connected thereto for opening and closing the circuit, means for imparting movement to said operating member, a movable member mounted upon said switch structure, said movable member having a resilient abut-

ment means thereon adapted to engage said operating member when said movable member is in one selective position for varying the movement of the operating member, yielding means for returning said movable member to retracted position, and a single flexible tension member control for said movable member for moving said movable member into any selective position, said yielding means serving to keep said tension member taut.

5. An automatic device for controlling a refrigerating system including an electric switch structure having pressure responsive means for initiating and terminating operation of the system, said switch structure having a projection thereon, a pivoted lever resiliently urged in one direction about the pivot, means for moving the pivoted lever in engagement with the projection and for varying the distance of the projection from the pivot of the pivoted lever to vary the effective moment arm and thereby vary the resistance of the resilient modifying means.

6. A refrigeration control structure having pressure responsive means for controlling the flow of a medium, said switch structure having a resilient modifying means including a projection and a pivoted lever resiliently urged against the projection, and means for varying the distance of the projection from the pivot of the pivoted lever to vary the effective moment arm and thereby vary the resistance of the resilient modifying means.

7. Refrigeration control mechanism including a member to be actuated, an operating member therefor, means for imparting a plurality of successive vibrations to said operating member, said operating member having a projection thereon, a pivoted lever resiliently urged in one direction about its pivot, said lever being pivoted to a movable carriage, and means for moving the movable carriage to cause the projection to engage the pivoted lever.

8. Refrigeration control mechanism including a member to be actuated, an operating member therefor, means for imparting a plurality of successive vibrations to said operating member, said operating member having a projection thereon, a pivoted lever resiliently urged in one direction about its pivot, said lever being pivoted to a movable carriage, and means for moving the movable carriage to cause the projection to engage the pivoted lever and to vary the distance of the projection from the pivot of the lever to vary the effective moment arm and thereby vary the resistance to the movement of the projection upon the pivoted lever.

9. A refrigeration regulating mechanism including a member to be actuated, an operating member therefor, a control mechanism for controlling the movement of the operating member, a remote actuating means for said control mechanism, tension type means connecting said remote actuating means and the control mechanism, and means to return the control mechanism to normal and retain the tension type connecting means taut.

CHARLES R. WAYMAN.
